GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA

INDICATING DEVICE

Application filed November 3, 1922. Serial No. 598,775.

My invention relates to indicating devices, and it has particular relation to such devices as may be employed in connection with transformers, circuit breakers or other electrical apparatus.

One object of my invention is to provide a reliable means for indicating a predetermined condition of a deoxidizing substance in an isolated atmosphere.

10 A second object of my invention is to provide a simple means for visually indicating a predetermined increase in weight of a deoxidizing agent.

15 A further object of my invention is to provide mechanical means for indicating a predetermined change in a chemical substance.

It has been ascertained that desirable results in the operation of transformers, circuit breakers and other electrical apparatus may 20 be secured if suitable means are provided for maintaining the insulating oil therein free from moisture. It has been found that it is desirable, also, to maintain an inert gas in the space above the insulating oil in order

25 to prevent the formation of an explosive mixture of oxygen and hydrocarbon gases. In the application of Otto H. Eschholz, Serial No. 592,898, filed Oct. 6, 1922, for improvement in gas filled tanks, and assigned to the 30 Westinghouse Electric & Manufacturing Company, is disclosed the use of phosphorus as a deoxidizing agent for the production of an inert atmosphere above the insulating oil and for the absorption of such moisture as

35 may be contained in that atmosphere.

It is well known that phosphorus in the presence of air absorbs oxygen, the resulting product being phosphorus pentoxide (P_2O_5). It has been determined that one

40 pound of phosphorus will unite with substantially 1.29 pounds of oxygen, the resulting product of phosphorus pentoxide weighing substantially 2.29 pounds. Accordingly, if phosphorus be used for the purpose described above, the condition of complete or substantially complete oxidation of the phosphorus may be known if a predetermined change in weight of the product be indicated in some suitable manner.

50 According to the present invention, I uti-

lize the above-described property of phosphorus to operate a visual indicating device when a predetermined change in weight has occurred. A lever arm is rotated through a predetermined angle when the weight of the compound reaches a predetermined value. 55

In the accompanying drawing, the single figure is a sectional view of a portion of a transformer tank with my invention embodied therein.

Referring to the drawing, a transformer tank 1, which may, for example, be filled with insulating oil 2 to the level indicated, is provided with a suitable cover member 3, which may be detachably connected thereto in any desired or suitable manner to secure airtight connection. The space 4 above the insulating oil is, under ordinary circumstances, initially occupied by air. 60

An indicating device 5, which is secured to the lower side of the cover member 3, comprises a lever arm 6 that is supported, at its central portion, by a bracket member 7. At one end of the arm 6, is suspended a container 8 into which may be placed a desired supply of phosphorus or other suitable deoxidizing agent. A counterweight 9 is suspended from the other end of the arm 6 to normally maintain the latter in its illustrated position in engagement with a stop member 10. 65

The arm 6 is provided with suitable depending lugs 12 in order that it may not slide longitudinally on the bracket 7 when it occupies an inclined position. A pin 13, which extends transversely of the arm 6, insures also that the latter may not move upwardly such distance that the lugs 12 do not engage the bracket 7. 85

Attached to the container 8 is an upwardly extending rod or indicator 14 that is surrounded by a tube 15 of glass or other suitable transparent material through which the position of the indicator may be observed. This tube, which may be similar to that employed in connection with steam and water gauges, is securely fastened to the cover member 3 by a screw-threaded portion 16. 90

It may be assumed that the container 8 is supplied with a charge of phosphorus or 100

other suitable deoxidizing agent and that the space 4 is filled with ordinary air. It may be assumed further that the enclosed atmosphere has been effectually isolated by the 5 securing of the cover member 3 in position. The phosphorus gradually absorbs oxygen from the surrounding air until the latter is reduced to substantially nitrogen which is an inert gas. As oxygen is absorbed, the weight 10 of the phosphorus increases correspondingly. A normal supply of deoxidizer may last for a comparatively long period, providing temperature changes within the tank cause the introduction of only small amounts of additional oxygen through leakage or other 15 causes.

However, when a predetermined weight is reached, the lever arm 6 is rotated in a counter-clockwise direction, as viewed in the 20 drawing, until the counterweight 9 engages a stop member 17, depending from the cover member 3. This position of the rod 14, which may be of any suitable color, indicates that the deoxidizing agent is substantially 25 saturated and that it should be replaced by a fresh supply.

While I have shown and described a device in which the indicating member is withdrawn from its normal position when a predetermined condition of the deoxidizing agent has been reached, it will be appreciated 30 that the rod may, if desired, be secured to the opposite end of the lever arm 6, whereby it is not visible until the predetermined condition is reached. It will be understood, also, that the indicating member may be attached to any desired portion of a movable member of the device.

While I have shown and described an arrangement in which the indicating mechanism is attached to the main cover of a tank for a transformer or other electrical apparatus, it will be understood that a separate detachable cover or man-hole cover may be 45 utilized in order that the main cover need not be removed to replenish the supply of deoxidizing agent.

A device constructed in accordance with my invention is of such simple and rugged 50 construction that it is not subject to damage or derangement by reason of rough handling of the apparatus in connection with which it is employed. The chemical condition of the deoxidizing agent is indicated by the 55 positive action of the mechanical device in accordance with physical properties of the deoxidizing agent.

I claim as my invention:

1. In combination, a tank containing an isolated atmosphere, an agent for absorbing a component of said atmosphere and weight-responsive means for indicating a predetermined condition of said absorbing agent.
2. In combination, a tank containing a fluid and an isolated atmosphere, an agent

for absorbing a component of said atmosphere and weight-responsive indicating means operative when said agent reaches a predetermined condition.

3. The combination with a container having therein a liquid medium and another medium comprising a plurality of gases, one of which with a gas evolved from said liquid medium is adapted to form an explosive mixture, of means for restraining formation of said mixture, and indicating means controlled by said first-named means. 70

4. The combination with a container having therein a liquid medium and another medium comprising a plurality of gases, one of which with a gas evolved from said liquid medium is adapted to form an explosive mixture, of means for absorbing said one of said gases, and indicating means controlled by said first-named means. 75

5. The combination with a tank containing a liquid medium, apparatus in said medium traversed by an electrical current, said apparatus under abnormal operating conditions evolving gas from said liquid medium, and a second medium in said tank and comprising a plurality of gases, one of which with said evolved gas forms an explosive mixture, of means for restraining formation of said mixture, and indicating means controlled by said first-named means. 80

6. The combination with a tank containing a liquid medium, apparatus in said medium traversed by an electrical current, said apparatus under abnormal operating conditions evolving gas from said liquid medium, and a second medium in said tank and comprising a plurality of gases, one of which with said evolved gas forms an explosive mixture, of means for absorbing one of said gases, and indicating means controlled by said first-named means. 85

7. The combination with a tank containing liquid hydrocarbon, apparatus in said liquid hydrocarbon traversed by an electrical current, said apparatus under abnormal operating conditions evolving gas from said liquid hydrocarbon, and a medium in said tank and comprising oxygen which with said evolved gas forms an explosive mixture, of means comprising a mass of phosphorus for absorbing the oxygen from said medium, and indicating means controlled by said first-named means. 90

In testimony whereof, I have hereunto subscribed my name this 25th day of October 1922. 100

GEORGE M. EATON.
